UNITED STATES PATENT OFFICE.

JAMES C. WALKER, OF DUNNIGAN, MISSOURI.

BOX-FASTENER.

SPECIFICATION forming part of Letters Patent No. 463,347, dated November 17, 1891.

Application filed August 15, 1891. Serial No. 402,744. (No model.)

To all whom it may concern:

Be it known that I, JAMES C. WALKER, a citizen of the United States, residing at Dunnigan, in the county of Polk and State of Missouri, have invented certain new and useful Improvements in Box-Fasteners; and I do hereby declare the following to be a full, clear, and exact description of the invention, such as will enable others skilled in the art to which it appertains to make and use the same.

My invention relates to an improvement in box-fasteners; and it consists in the certain peculiar features of construction and arrangement of parts more fully hereinafter described, and definitely pointed out in the claims.

The object of my invention is to provide a fastening for boxes, crates, and other similar articles, which will be simple in its construction, cheaply manufactured, and quickly applied and adjusted. This object I accomplish by the construction illustrated in the accompanying drawings, wherein like letters of reference indicate like parts in the several views, and in which—

Figure 1 is an end elevation, and Fig. 2 is a perspective view.

In the drawings, A represents a box having a cover B, provided with cleats b on its ends 30 overhanging the sides of the box. Through these cleats and the end portions of the cover are extended metal rods C, their ends passing through the cleats and cover and formed into eyes c, the upper portions of the rods extending entirely across the ends of the cover 35 on the upper face, as at c', at which points they are secured in place by staples c².

D represents a bail having diverging sides terminating in a rounded bearing or apex, 40 and having its upper end hooked through and secured to the eyes c of the rods C on the cover.

Pivotedly secured on the ends of the box, near the lower portions thereof, are cams E, 45 having a grooved periphery and a lever-arm e. These cams occupy a position between the sides of the bail, which is arranged to fit over the grooved end thereof.

F is a spring-catch secured to the end of 50 the box, arranged with its inclined side in the path of the lever, so that as the lever is forced around it rises up on the inclined face of the spring, dropping off from the end thereof, and is thus prevented from being moved backward.

In operation the cover is placed on the box and the bail swung down over the cams, the latter being turned to throw the lever-handle in the rear of the spring. The lever is then forced forward, turning the cam and tightly pressing 60 the same against the bail resting in the groove thereof. A backward or forward movement of the lever is prevented by the spring and the side bar of the bail, between which it rests when the box is fastened. By extending 65 the rod across the top of the box I add additional strength to the cover and also more equally distribute the strain.

It is to be understood that the above construction is to be applied to both ends of the 70 box.

I am aware that many minor changes in the construction and arrangement of the parts of my device can be made and substituted for those herein shown and described without in 75 the least departing from the nature and principle of my invention.

Having thus described my invention, what I claim as new, and desire to secure by Letters Patent, is—

1. In a box, the combination, with the ends and top, the latter projecting beyond the former, of bails secured to the overlapping ends of the top, cams located on the ends of the box over which the bails engage, levers on 85 the cams, and springs arranged in the path of the levers for retaining the same in adjusted positions, substantially as described.

2. In a box-fastener, the combination, with the ends of a box, of a cover having overlapping ends, a rod passing through the overlapping ends of the cover across the top thereof, eyes formed in the ends of the rod, a bail having its ends secured in the eyes and extending down to a point near the bottom of 95 the box, a cam on the end of the box, having a grooved periphery with which the bail engages, a lever on the cam between the sides of the bail, and a spring-catch with which the lever comes in contact, substantially as described.

In testimony whereof I affix my signature in presence of two witnesses.

JAMES C. WALKER.
